CLAIM

The ornamental design for an attachment head for a power tool as shown and described.

DESCRIPTION

FIG. 1 is a perspective view of an attachment head for a power tool.

FIG. 2 is a front view of the attachment head of FIG. 1.

FIG. 3 is a rear view of the attachment head of FIG. 1.

FIG. 4 is a left view of the attachment head of FIG. 1.

FIG. 5 is a right view of the attachment head of FIG. 1.

FIG. 6 is a top view of the attachment head of FIG. 1; and, FIG. 7 is a bottom view of the attachment head of FIG. 1. The portions in broken lines form no part of the claimed design.

The unshaded surface within the innermost solid line circle shown in FIG. 3 forms no part of the claimed design.

1 Claim, 7 Drawing Sheets
